UNITED STATES PATENT OFFICE.

WILL C. NEAHR, OF DENVER, COLORADO, ASSIGNOR TO THE PROTECTIVE SIGNAL MANUFACTURING COMPANY, OF DENVER, COLORADO, A CORPORATION OF COLORADO.

RAILROAD-CROSSING SIGNAL.

1,268,381.

Specification of Letters Patent. Patented June 4, 1918.

Application filed June 18, 1916. Serial No. 103,451.

To all whom it may concern:

Be it known that I, WILL C. NEAHR, a citizen of the United States, residing at Denver, in the county of Denver and State of Colorado, have invented new and useful Improvements in Railroad-Crossing Signals, of which the following is a specification.

The present invention relates to visual signals of the movable type, and more particularly to those which display a warning signal at railroad crossings and the like.

The primary object is to provide a simple apparatus of effective character, which will display a movable danger signal that is visible in the day-time, and also an illuminated signal at night whenever there is danger at a crossing.

A further object is to provide mechanism which is not liable to derangement or damage from the elements, the parts being simple and completely inclosed.

An embodiment of the invention that has proven practicable is illustrated in the accompanying drawings, wherein:—

Figure 1 is a view in elevation of the apparatus, with a portion of the casing broken away.

Fig. 2 is a detail view on an enlarged scale of the actuating means for the signal arm.

Fig. 3 is a view in elevation of the circuit controller for the electro-magnet.

Fig. 4 is an end elevation of the same.

Fig. 5 is a detail view showing the electrical connections for the lamp between the movable arm and the stationary parts.

Fig. 6 is a vertical sectional view taken substantially on the line 6—6 of Fig. 3.

Fig. 7 is a view similar to Fig. 6 of a portion of the mechanism.

Fig. 8 is a diagrammatic view showing the electrical connections.

Similar reference numerals designate corresponding parts in all the figures of the drawings.

In the embodiment disclosed, a suitable post or standard 9 is provided, having a base 10, and provided, if desired, with the usual crossing alarm bell 11 and signal lamps 12. Supported on the upper portion of the standard 9 by U-bolts or clips 13 is a bracket 14, which terminates in a casing 15 having opposite side walls 16 perforated for display purposes. Thus, in the embodiment

disclosed the word "Danger" as shown at 17 is cut out of said faces.

Supported in the lower portion of the casing 16 is a base 18 having an opening 19, on opposite sides of which are ears 20. 60 These ears support a fixed pivot 21, on which is journaled an upright swinging signal arm 22. This arm extends downwardly through the opening 19 of the base 18, and through an opening 23 formed in the bottom of the 65 casing. It carries a depending target or signal blade 24 that extends a considerable distance below the casing 15, where it is clearly visible. The upper end of the arm is provided with one or more lamps, as 25, two 70 being illustrated in the present embodiment, which lamps are disposed in opposite directions, and will swing behind the word "Danger" when the arm 22 is oscillated, as will be evident. 75

The lamps are electrically connected, as illustrated at 26 with a pair of spring contact fingers 27, which fingers have their free ends in slidably engagement with a pair of fixed contact plates 28 mounted on a ring 80 29 of insulating material that is suitably supported on the pivot 21. The plates 28 are located in a suitable circuit 30, which includes a source of electrical energy, shown diagrammatically at 31 in Fig. 8. 85

Supported on the base 18 within the casing 15 at one side of the arm 22, is an electro-magnet 32, and on the opposite side of said arm 22 to the electro-magnet is a post 33 having upper and lower roller bearings 34, 90 between which operates one end of an armature 35, said armature extending into the electro-magnet 32 and having roller bearings 36 in the inner head of said electro-magnet. This armature 35, as shown in Fig. 2, has 95 a slot 37, through which the signal arm 22 passes, and said arm 22 has a longitudinal slot 38. A roller 39, journaled on the armature 35 and located in the slot thereof, is engaged in the slot 38 of the arm 22, and thus a connection is provided between the two parts which will effect the swinging of the arm 22 upon the reciprocation of the magnet. Shock absorbing springs 40 are located on the armature 35 on opposite sides 100 of the post 33 and are arranged to bear against the same, accordingly as the armature approaches the limit of its movement in opposite directions. A counterweight 41 is adjustably mounted on an arm 42 which 105 110

projects from the side of the arm 22 opposite to that on which the electro-magnet 32 is located.

The electro-magnet 32 is located in the 5 circuit 30 by having its poles electrically connected with the plates 28 through the medium of the wires 43 and 44 and binding posts 45 and 46. The wire 44 includes a circuit controller for said electro-magnet, 10 and as shown, this circuit controller consists of a contact element 47 having a carbon contact block 48, which is engaged and disengaged by another carbon block 49 carried by a swinging contact spring 50 located 15 thereover. This spring 50 is engaged by a cam 51 journaled on the fixed pivot 21 and arranged to be held in any position in which it is left by the friction washers 52 located on opposite sides of said cam and bearing 20 against the same. This cam is provided with a slot 53, in which operates a pin 54 carried by the arm 22. The pin 54, as will be clear, has a limited play in the slot, but the amount of this play can be varied by 25 abutment screws 55 threaded through the opposite edges of the cam, and having their inner ends entering the ends of the slot 53. The upper end of the cam is in the form of a rounded projection 56 that has an oscillating bearing on the under side of the 30 arm 50.

Briefly described the operation is as follows: Whenever the circuit 30 is closed through the medium of any well known 35 mechanism, as for example, a circuit closer indicated broadly at 57 in Fig. 8, it will be evident that if the contact elements 48 and 49 are in engagement, the electro-magnet will be energized. As a matter of fact, these 40 contact elements are normally in engagement when the signal is at rest, inasmuch as the counterweight 41 will hold the arm 22 in an inclined position, and the cam 51 will be likewise inclined. When the electro-magnet 45 is thus energized, the armature 35 will be drawn into the same, thereby swinging the upper end of the arm 22 to the left. As a result, the pin 54 will be moved until it strikes the left hand abutment screw 55, 50 whereupon the cam 56 will be moved to the position shown in Fig. 3, which will cause the arm 50 to be raised and break the contact between the elements 48 and 49. As a result, the electro-magnet will be deenergized, and the weight 41 will react to swing 55 the arm in the opposite direction, whereupon the cam 51 will be moved to the right, and from its position supporting the arm 50, so that the contacts 48 and 49 will again 60 engage. The electro-magnet then becomes reenergized, and it will be understood that this action will be repeated as long as the circuit 30 is closed. As a consequence, the target 24 will be swung back and forth, giving 65 a visual display of danger. At the same

time, the circuit will be closed through the lamps 25, and said lamps will consequently be illuminated. As a result, at night the word "Danger" will be displayed, and this danger signal will be given a varying aspect 70 by the movement of the lamps within the casing.

From the foregoing, it is thought that the construction, operation and many advantages of the herein described invention will 75 be apparent to those skilled in the art, without further description, and it will be understood that various changes in the size, shape, proportion, and minor details of construction, may be resorted to without departing 80 from the spirit or sacrificing any of the advantages of the invention.

Having thus fully described my invention, what I claim as new, and desire to secure by Letters Patent, is:—

1. In a signal of the character set forth, the combination with a casing having a perforated display face, of a swinging arm having one end located within the casing and the other end projecting therefrom, means 90 for swinging the arm, and a lamp carried by the portion of the arm within the casing.

2. In a signal of the character set forth, the combination with a casing having a perforated display face, of a swinging arm having one end located within the casing and the other end projecting therefrom, a motor within the casing for swinging the arm, and a lamp carried by the portion of the arm within the casing.

3. In a signal of the character set forth, the combination with a casing having a display face, of an arm pivoted in the casing and having a target carried by its lower end and depending below said casing, illuminating means on the upper end of the arm that oscillates behind the display face, an electro-magnet within the casing, an armature for the electro-magnet connected to the arm, and means for controlling the energization and deenergization of the magnet located within the casing and also connected to the arm.

4. In a signal of the character set forth, the combination with a swinging signal arm, of an electro-magnet, a reciprocating armature for the magnet, extending transversely of the arm and having a slot through which the arm passes, said arm also having a slot, and a device located in both slots and constituting a connection between the armature 110 and arm.

5. In a signal of the character set forth, the combination with a support, of a swinging signal arm pivoted on the support and having a longitudinal slot, an electro-magnet 125 on one side of the arm, a guide-way on the other side of the arm, a reciprocating armature extending transversely of the arm and having a slot through which the same passes, said electro-magnet having a sliding bearing 130

in the guideway, and a roller bearing located in the slots and constituting a connection between the armature and signal arm.

6. In a signal of the character set forth, the combination with a swinging signal arm, of an electro-magnet for actuating the same, a pivot for the arm, a circuit controller for the electro-magnet, including a movable member, a cam having a friction mounting 5 on the pivot and engaging the movable member of the circuit controller for operating it, and means moving with the arm and having a loose play engagement with the cam for moving the same.
- 10 7. In a signal of the character described, the combination with a pivot, of a signal arm

and a cam independently mounted on the pivot, an electro-magnet for actuating the arm and cam, a circuit controller for the electro-magnet operated by the cam, and a 20 connection between the signal arm and cam at one side of the pivot for operating one from the other, said connection having a limited lost motion.

In testimony whereof I have hereunto set 25 my hand in presence of two subscribing witnesses.

WILL C. NEAHR.
